LOCKING TEETER-BAR SWITCH

Filed Sept. 20, 1949

UNITED STATES PATENT OFFICE

2,616,012

LOCKING TEETER-BAR SWITCH

Arthur C. Gaynor, Stratford, Conn.

Application September 20, 1949, Serial No. 116,778

4 Claims. (Cl. 200—169)

1

This invention relates to electric switches, and more particularly to snap or toggle switches of the type having a teeter bar as an operating member.

Small toggle or snap switches are commonly used for appliances, electric typewriters, accounting and other business machines to switch these on and off. At times the operator of the machine finds it necessary to leave the machine with work in it, and under such circumstances it is highly desirable to prevent casual, inadvertent, or mischievous operation of the machine during the operator's absence. For example, in bookkeeping, tabulating or adding machines, and also in typewriters, during the operator's absence the machine might be operated by another accidentally or unintentionally and cause the work to be spoiled or inaccurate. This may or may not be noticed by the operator upon his return, and in either event has undesirable consequences.

An object of the present invention is to provide an improved and simplified on-and-off, toggle or snap switch, particularly for electric appliances, business machines and the like, which may be very easily and quickly locked in its "off" position so as to discourage tampering with the machine or accidental operation of the machine during an operator's absence.

Another object of the invention is to provide an improved toggle or snap switch adapted for the above purpose, which may be locked in either its "off" or "on" position.

A further object of the invention is to provide an improved locking-type electric switch as characterized above, which is extremely simple in construction and economical to fabricate.

A still further object of the invention is to provide an improved electric switch in accordance with the foregoing, which may be very quickly and easily locked or unlocked by the operator.

In accomplishing the above objects I provide a toggle or snap switch mechanism mounted in a casing which may be either of the panel-mounting type or the feed-through type. The casing carries a teeter-bar operator for the switch mechanism, adapted to occupy different "on" and "off" positions. On portions of said teeter bar and casing I provide cooperating means for releasably locking the bar in one or the other of its positions, against casual movement. To actuate the locking means a manually-operable member, preferably in the form of a recessed head stud, is provided, which is rotatably carried by the teeter bar operator. The locking

2

means, in the embodiments of the invention illustrated herein, comprises a lug on the teeter bar and a cooperable shoulder on the casing, the said lug being actuated in response to movement of the recessed head studs.

When it is desired to lock the switch in either "off" or "on" position, I provide duplicating locking and actuating assemblies on the teeter bar and casing, which may be made operative for either position of the teeter bar.

Preferably the recessed head studs are of the type known commercially as "Allen head," that is, they have hexagonal recesses requiring an hexagonal key to operate them. Therefore a person other than the operator of the machine cannot employ devices such as nail files, screw drivers and the like to unlock the switch, but will need a proper-fitting hexagonal key, such as an "Allen" key.

Other features and advantages will hereinafter appear.

In the accompanying drawings:

Figure 1 is a longitudinal sectional view through an improved teeter-bar toggle switch embodying the invention, said switch being of the feed-through type.

Fig. 2 is an inside plan view of the upper half of the switch of Fig. 1, indicated by the lines 2—2 in this figure.

Fig. 3 is a fragmentary plan view of the teeter bar of the switch of Fig. 1.

Fig. 4 is a fragmentary longitudinal sectional view of a teeter bar operator illustrating another embodiment of the invention wherein the teeter bar may be locked either in "off" or "on" position.

Fig. 5 is a view like Fig. 1 but illustrating a panel-type switch, and further illustrating a modified form of locking means; and

Fig. 6 is a fragmentary detail, in perspective, of the locking means shown in Fig. 5.

Referring to Figs. 1 and 2 the improved locking toggle switch shown therein comprises a casing 10 having a lower part 11 and an upper part 12 secured together by the usual draft screws. Within the casing 10 an electric switch mechanism 13 is provided, having a switch blade 14 and a toggle or snap mechanism 15 which is actuated by a finger 16 of a teeter bar 17 pivotally carried by the casing part 12.

As shown in Fig. 3, the teeter bar 17 may have the indicia "off" and "on" respectively on its faces 18 and 19, the said faces being angularly disposed with respect to each other and so arranged that, 55 for the two possible positions of the teeter bar,

one or the other faces 18, 19 is flush with the exterior of the casing part 12.

For the purpose of providing a simple and effective locking means whereby the teeter bar 17 may be locked in "off" position, I provide a manually operable member 20 in the form of a recessed head Allen-type stud which is rotatably carried by the left-end portion of the teeter bar 17, as viewed in Fig. 1. The head of the stud 20 is recessed into the teeter bar so that the face of the stud is substantially flush with the surface 18 of the bar.

At its lower end the stud 20 mounts a lug 21 which extends laterally from the shank of the stud a distance sufficient to enable it to project into a recess 22, Fig. 2, in the casing 10. As shown in Fig. 1, the recess 22 has an upper wall 23 which constitutes a shoulder arranged to be engageable with the lug 21 when the latter is in a locking position shown in Fig. 2. The shape of the lug 21 is such that when the stud 20 is rotated to bring the lug into the dot-and-dash position 24 shown in Fig. 2, the lug will not project into the recess 22, but, instead, will clear the shoulder 23, thereby enabling the teeter bar 17 to be freely operated to actuate the switch from "off" to "on" and vice versa. When, however, the lug 21 is in the position shown in Fig. 2, the teeter bar 17 will be locked in the "off" position of Fig. 1, and a person cannot either casually or inadvertently or intentionally operate the switch to "on" position unless he first turns the stud 20 to bring the lug 21 to the unlocking position 24.

Thus an operator of the machine which has the present improved locking switch may take the precaution of preventing his machine being operated during his absence by merely inserting an Allen wrench in the recessed head of the stud 20 and turning it to lock the switch in its "off" position.

Since a small hexagonal tool or instrument having the shape of an Allen wrench is relatively uncommon in offices and the like, a person desiring to operate the switch will find it difficult to do so if he does not have the proper wrench to perform the unlocking operation. Instruments such as screw drivers, nail files and the like will not be effective to turn the stud 20, particularly since the hexagonal recess thereof is of extremely small dimension.

I have thus provided, by the above structure, an extremely simple and practical means for locking an appliance or business-machine switch in its "off" position. Relatively few parts are involved in the locking means and therefore it may be easily and quickly fabricated at low cost. Moreover it may be very easily or conveniently actuated by the operator of the machine, requiring only the possession of the proper size Allen wrench or key.

Another embodiment of the invention is shown in Fig. 4 wherein a teeter bar 26 is provided, having at both its ends recessed-head studs 27 and 28 carrying locking lugs 29 and 30 respectively. The lug 29 may be swung to project it into a recess 31 in the casing part 32 of the switch, to engage a shoulder 33 formed by a wall of said recess. Likewise the lug 30 carried by the stud 28 may be swung to project it into a recess 34 in the casing part 32, having a shoulder 35 for engagement by said lug.

According to this construction the teeter bar 26 may be locked in either its "on" or "off" position.

A modification of the invention is shown in

Figs. 5 and 6. In these figures the teeter bar 36 carries a recessed-head stud 37 provided at its inner end with a tab or blade 38 having oppositely disposed notches 39 providing undercuts. The stud 37 has a press-fitted collar 37a to retain it in place on the teeter bar 36.

The switch of Figs. 5 and 6 has a casing 40 provided with an insert 41 in the form of a socket-shaped member having a slot 42 adapted to receive the blade 38 of the stud 37. As shown in Fig. 5, when the teeter bar 36 is in the "off" position, the blade or key 38 will extend into the socket member 41 through the slot 42 thereof, and if the stud 37 should be turned to the position shown in Fig. 5, the key 38 will become locked to the member 42 and prevent actuation of the switch 36.

While I have shown the studs 20, 27, 28 and 37 as being of the recessed-head Allen type, obviously other recessed members may be substituted therefor, requiring special or odd shaped keys, and tumbler locks may also be used where it is imperative that inadvertent or casual operation of the switch be prevented.

Variations and modifications may be made within the scope of the claims and portions of the improvements may be used without others.

I claim:

1. In an electric switch having a casing, a switch mechanism in the casing and a teeter bar mounted on the casing for movement between "on" and "off" positions, said bar actuating said mechanism, the improvement which comprises: cooperating means on portions of said teeter bar and casing, inaccessibly located within the casing, for releasably locking the bar in one of its positions on the casing, said means comprising a movable lug on the bar and a shoulder on the casing alongside the bar, engageable by said lug when the latter is projected from the side of the bar; a member movably mounted on one of said portions of the casing or teeter bar, said member being shaped and located to prevent its being grasped by hand and having means engageable by a key to move the member; and means controlling said movable lug in response to movement of said member.

2. In an electric switch having a casing, a switch mechanism in the casing and a teeter bar mounted on the casing for movement between "on" and "off" positions, said bar actuating said mechanism, the improvement which comprises: a member movably mounted on said teeter bar, said member being shaped and located to prevent its being grasped by hand and having means engageable by a key to move the member; and means on said bar and casing, inaccessibly located within the casing, for releasably locking the bar in one of its positions in response to actuation of said member, said means including a movable lug on the teeter bar, actuated by said member and projectable from the side of the bar, and including a shoulder on the casing alongside the teeter bar, engageable by said lug when the latter is projected.

3. In an electric switch having a casing, a switch mechanism in the casing and a teeter bar mounted on the casing for movement between "on" and "off" positions, said bar actuating said mechanism, the improvement which comprises: cooperating means on portions of said teeter bar and casing, inaccessibly located within the casing, for releasably locking the bar in one of its positions on the casing, said means comprising a movable abutment on the bar and a cooperating

fixed shoulder on the casing engageable by said movable abutment when the latter is shifted to locking position; a member movably mounted on the teeter bar, said member being shaped and located to prevent its being grasped by hand and having means engageable by a key to move the member; and means actuating said movable abutment in response to movement of said member.

4. The invention as defined in claim 3 wherein the movable abutment comprises a notched member and said fixed shoulder comprises a slotted socket to receive said notched member.
